UNITED STATES PATENT OFFICE.

WILLIAM C. PERKINS, OF WORCESTER, MASSACHUSETTS, ASSIGNOR TO THE WIRE GOODS COMPANY, OF SAME PLACE.

DESIGN FOR A WIRE HANDLE.

SPECIFICATION forming part of Design No. 14,038, dated July 3, 1883.

Application filed April 4, 1883. Term of patent 14 years.

To all whom it may concern:

Be it known that I, WILLIAM C. PERKINS, of Worcester, in the county of Worcester and State of Massachusetts, have invented a new and original Design for Wire Handles; and I do hereby declare that the following is a full, clear, and exact description of the same, reference being had to the accompanying drawings, forming a part of this specification, and in which—

Figure 1 represents a top or plan view, and Fig. 2 a side view, of my aforesaid new design for wire handles.

Heretofore wire handles have been made in a curved or elliptical form, or with a straight shank and curved ends next to their points of fastening, or, in other words, by forming a continuous curve between the two eyes or said points of fastening of the handle.

The main feature of my design consists in a bend, A, formed at each end of the handle at an angle of forty-five degrees to the shank or straight part B of said handle and to the eyes C for fastening the same in position. Said

bends A do not extend entirely to the eyes C 25 from the long straight part B, intervening bends, D, being formed in the wire between said miter-bends A and the eyes C at right angles to shank or straight part B and said eyes or the line of fastening of the handle, as is shown 30 in Fig. 2 of the drawings. This, as will be seen, makes a unique and very tasty design for a wire handle, being much more pleasing in appearance to the eye than the old style of handles now in use.

Having described my new design for wire handles, what I claim therein as my invention, and desire to secure by Letters Patent, is—

The design for a wire handle herein shown and described, the same consisting of the long 40 straight part or shank B, miter-bends A A, right-angle bends D D, and fastening-eyes C C, substantially as set forth.

WILLIAM C. PERKINS.
